UNITED STATES PATENT OFFICE.

FRED A. HOLMES, OF BELFAST, MAINE.

ADZ.

Application filed April 7, 1922. Serial No. 550,381.

To all whom it may concern:

Be it known that I, FRED A. HOLMES, a citizen of the United States, residing at Belfast, in the county of Waldo and State of Maine, have invented certain new and useful Improvements in Adzes; and I hereby declare that the following is a full, clear, and exact description thereof, reference being had to the accompanying drawings, which 10 form part of this specification.

This invention relates to improvements in cooper's adzes and the object of my invention is to provide a novel adz which the cooper may turn on either side, and drive a 15 metal hoop down flush with the end of the barrel, or cask, without damage to the hoop or injury to the stave. Another essential novel feature of my invention is the provision of an adz with broad flat sides formed 20 by the flanges, which enables me to provide a light adz which can be readily used with one hand. A cooper's adz should only weigh from two to four pounds complete with handle, and if made solid is too heavy. Here- 25 tofore it has been necessary for the cooper to use some additional tool with the necessary flat surface to do the same work, resulting in loss of time; but by using my improved adz the hoop may be driven in place without 30 the use of extra tools, and without breaking or otherwise injuring the thin metal hoop.

The ordinary cooper's adz can not be used to drive down the hoops as the hoops on a barrel are made of thin soft material, and 35 when driven down with the ordinary adz having only a small surface to strike with, the edge of the hoop will be marred and frequently broken, as the ordinary cooper's adz has no flat surface on its sides as set 40 forth in my invention.

In the accompanying drawings I have illustrated an adz embodying my invention, and I will explain the same with reference to said drawings, and summarize in the 45 claim, the invention for which protection is desired.

In the drawings:

Fig. 1 is a perspective view of my novel adz.

50 Fig. 2 is a longitudinal section through the adz.

Fig. 3 is a transverse section on the line 3—3, Fig. 2.

The adz is preferably formed of a single 55 piece of metal comprising a body 1, head 1^a,

side flanges 1^b, cutting blade 1^c, and handle socket 1^d. As shown in Figs. 1 and 2, body 1 comprises the body of the adz, and has a substantially flat upper portion adjacent the head 1^a, the lower portion of said body being curved as shown in the drawings on a relatively large radius, and terminating in the cutting blade 1^c, in the usual manner.

At the upper end of body 1, is a head 1^a, which projects inwardly from the body 1 and is formed integral therewith, its top surface being substantially perpendicular to the body, forming a flat hammer surface. This head 1^a may be of any desired width and thickness.

At either side of body 1 are formed inwardly projecting flanges 1^b as shown in Fig. 3, whose outer surfaces are perpendicular to the outer surface of the body; said flanges 1^b extending from the head 1^a, terminating with, and fairing into the curved lower portion of body 1, adjacent the cutting blade 1^c thereof, as shown in Figs. 1 and 2.

Intermediate the head 1^a and cutting blade 1^c, and extending between the flanges 80 1^b is a cross-bar 1^e, from which projects a handle socket 1^f, formed integral with the body 1, said cross bar 1^e connecting the flanges 1^b, and reinforcing the same. The socket 1^f has a slightly conical bore 1^f to 85 receive a suitable handle (not shown) for the adz, which handle may be secured in the bore 1^f in any suitable manner.

The body 1 is preferably tapered from head 1^a to the cutting edge 1^c, the latter being 90 greater in width than the head 1^a; and the cutting edge is sharpened in the usual manner.

My novel adz can be used as an ordinary adz for cutting and hammering, but in addition, the cooper may turn the adz on either side, and drive the hoops down, flush with the end of the barrel, with either flat surface thereof, formed by the flanges 1^b, without damage to the hoop or injury to the 100 staves, and without having to employ any other tool, thereby saving time and tools.

Barrel hoops are generally made of thin material so that they can bend around the barrel without breaking. But if the hoops 105 are driven down with the ordinary adz having a small hammering surface (like 1^a), the hoops are frequently broken. But with my improved adz the hoops may be quickly and readily driven in place by the broad 110

flat surfaces 1^b, without injury to the hoops or marring of the barrel.

The ordinary cooper's adz has no flat surface on its sides, and the hoops have to be driven with the face of the hammer ends having a 1½ or 1¾ inch surface, which surface is made to strike the driver with, and not to drive the hoop direct. But with my novel adz with the broad flat driving surfaces provided by the flanged portions 1^b, the cooper can turn the adz sideways and drive the hoops on the barrel without having to use the driver, and without danger of breaking the hoops or the barrel, and thus, in practical use, the invention has resulted in great saving in the loss by breakage of

hoops, and in facilitating the making of barrels.

I claim:

A cooper's adz, comprising a body having 20 a hammer head at one end and a curved cutting blade at its lower end, and flanges on each side connecting the head with the blade, the outer surfaces of said flanges being flush with the side edges of the body, a cross 25 bar connecting the flanges adjacent the mid-point of said body having a socket to receive the handle, all formed integral, substantially as and for the purpose described.

In testimony that I claim the foregoing 30 as my own, I affix my signature.

FRED A. HOLMES.
